PRESSURE-FLUID OPERATED TOOL

Walter E. Northcutt, Melrose, Mass., assignor to H. K. Porter, Inc., Somerville, Mass., a corporation of Massachusetts

Application July 3, 1956, Serial No. 595,709

4 Claims. (Cl. 30—180)

This invention relates to hydraulically operated tools such as those used for cutting steel bars and other heavy work beyond the range of hand-operated tools, the object being to provide an improved construction for such a tool wherein means are provided to prevent entry into the mechanism of foreign particles with resulting wear or deterioration of the tool. For instance, in steel mills such tools are used for trimming steel rod after hot rolling, and there is always scale on the rod which is being cut. As each cut is made small particles of scale are broken away and fall into the opening between the blades and if they are drawn into the bearing surfaces between the moving parts, they may cause cutting or galling, so that the ram of the tool will stick or the bearings be enlarged until side movement is excessive and the blades will no longer be in alignment.

My invention will be well understood by reference to the following description of the illustrative embodiment thereof shown for example in the accompanying drawings, wherein:

Fig. 1 is a perspective of the tool;

Fig. 2 is a view chiefly in longitudinal section on a larger scale; and

Figs. 3 and 4 are diagrammatic details, unrealistic as to the dimensions shown.

The tool herein shown is a portable tool in the sense that it may be brought to the work and may be in part positioned or guided by hand and its cutting cycle is under manual control.

Referring now to the drawings, and more particularly to Fig. 2, the cutting elements of the tool are supported by a C-frame 10 having a fixed cutter 12 mounted on one arm of the C, while the other arm is provided with a guiding and bearing surface herein formed by a liner or bushing 14 for the ram 16 of the hydraulic mechanism on the distal end of which is mounted a cooperating tool 18 the edge of which, when the ram is moved to the left from the position of Fig. 2, cooperates with the edge of the cutter 12 for severing the work.

The C-frame 10 is herein at least effectively integral with a head 19 closing the left-hand end of a cylinder 20, in which reciprocates a single acting piston 22, the ram 16 in this instance being the piston rod. A head 24 closes the right-hand end of the cylinder and forms a working chamber to which hydraulic fluid may be admitted through the nipple 26 from the flexible conduit 28, Fig. 1, leading to a source of supply. When the fluid is so admitted the piston 22 moves to the left on the power stroke and on the exhaust stroke it is returned by the compression springs 30 interposed between the piston and the head 19. An orienting pin 32 on the piston enters a hole 34 in the head 19 to orient the parts.

Referring to Fig. 1 in the tool shown a ring 36 surrounds the cylinder and provides means for suspending the tool by a flexible connection from an overhead point. A handle 38 mounted on the nipple 26 provides for steering the tool and a trigger 40 on the handle controls the operation of the hydraulic mechanism. These de-

2

tails are here described because illustrated in Fig. 1, but they are of no importance to the invention and are not shown in Fig. 2.

The head 19 at the left of the cylinder defines with the piston a chamber of variable size. The head is packed with an O-ring 42, but on movement of the piston to the right air may enter this chamber through an inwardly opening valve 44 loaded by a light spring. A screen 46 and filter 48 outwardly of the valve prevent foreign particles from entering with the air.

On the exhaust stroke of the mechanism when the piston moves to the right a charge of air is drawn into the chamber. On the return stroke the valve is closed, the air is compressed and can escape only between the ram 16 and the bushing 14. No clearance is shown between these parts in Fig. 2 because that would be misleading. It will be understood that they are a good sliding fit, as is mechanically desirable, but that they would not effectively retain pressure fluid unless packed.

The control of this charge of air is effected by what is in a sense a packing ring 50, although installed reversely to the usual manner, and which functions also as a yielding valve. This ring is shown with some exaggeration most clearly in Figs. 3 and 4, and is generally of channel shape section with a base 52 and outwardly flaring yielding lips 54 and 56. The ring may be molded from plastic material of suitable resiliency. I have found nylon to be suitable. I believe also that certain silicone rubbers would serve, but have not fully tested them under conditions of use. Tetrafluoroethylene is another possibility. This ring may be installed in a suitable groove in the ram 16 with the lips projecting axially outwardly toward the distal or free end of the ram which carries the tool 18. In Figs. 3 and 4 the clearance between the ram and the cylinder is much exaggerated. In practice the radial thickness of the base 52 of the ring may be somewhat smaller than the nominal clearance between the bottom of its groove and the liner, say two to five thousandths of an inch. On the other hand the lips may be so molded

that the distance between them is slightly greater than this nominal clearance, again say two to five thousandths of an inch, and therefore they are under a slight compression in Fig. 3. When the ram is moving toward the right, due to spring pressure, and is exhausting the hydraulic fluid to the right of piston 22 the lip 56 bears on the liner 14 and slides over it with a wiping action as shown in Fig. 3. This lip not only is a mechanical barrier against the entry of foreign matter past it, but also serves as a valve, due to the higher pressure outside the tool tending to spread the lips of the wiper. It may be noted that as the piston 22 moves to the right it creates an enlarging volume with a pressure below atmospheric. The reduced pressure within the tool chamber allows outside atmospheric pressure to unseat the ball valve 44 until equilibrium of pressures is established, at which point ball valve 44 closes.

Now as the piston moves toward the left the valve 44 is closed and pressure begins to build up in the chamber as its volume decreases. In the initial stage of the movement the lip 56 will retain the position shown in Fig. 3 and act as a mechanical wiper or squeegee moving on the liner 14. As pressure builds up however it may flex inwardly to the position diagrammed in Fig. 4, permitting flow of air outwardly, and the web portion 52 of the ring may move downwardly to the bottom of its groove, increasing the clearance for air escape past the ring. This stream of air flows outwardly between the bearing surfaces and around the blade 18, lessening the possibility of scale working in between the former.

I am aware that the invention may be embodied in other specific forms without departing from the spirit or essential attributes thereof, and I therefore desire the present

embodiment to be considered in all respects as illustrative and not restrictive, as is in fact clear in several matters from the description itself. Reference is to be had to the appended claims to indicate those principles of the invention exemplified by the particular embodiment described and which I desire to secure by Letters Patent.

I claim:

1. A pressure-fluid operated tool comprising a cylinder having a piston therein, a ram carried by the piston having a tool mounted thereon, a closure head for the cylinder through which the ram passes defining within the cylinder an air receiving chamber, guiding means for the ram, an inwardly opening valve for admitting air to the chamber on the exhaust stroke of the piston and yieldable means providing for discharge of entrapped air from the chamber over the guiding surfaces on the power stroke of the piston.

2. A pressure-fluid operated tool comprising a cylinder having a piston therein, a tool-carrying member carried by the piston, a closure head for the cylinder through which said member passes defining within the cylinder an air receiving chamber, means associated with the head providing an elongated external bearing for said member, a tool on the end of said member and packing means between said member and bearing having a resiliently flexible axially outwardly extending lip which bears on one

of them during the exhaust stroke to exclude passage of air to the chamber during the exhaust stroke and yields to permit passage of air over the bearing surfaces during the power stroke.

5 3. A pressure-fluid operated tool comprising a cylinder having a piston therein, a ram carried by the piston having a tool at its distal end a bearing in which the ram slides, a packing ring between ram and bearing having a lip extending axially outwardly and resiliently yieldable radially inwardly, means controlled by movement of the piston for drawing in a charge of air on one stroke of the piston and means for releasing it to the bearing surfaces at the inward side of the lip on the other stroke.

10 4. A tool comprising a frame having a pair of cooperating cutters mounted thereon one being mounted on a ram to move to and from the other, the frame having a bearing for supporting and guiding the ram, a packing between bearing and ram adjacent the tool normally biased to exclude passage of air therethrough from the tool side but yieldable to pressure from the other side, pressure-fluid operated means for reciprocating the ram, and means operated thereby for discharging air under pressure to the bearing surfaces at said other side of the packing.
